UNITED STATES PATENT OFFICE.

FRED N. J. OHLSON, OF PIERSON, FLORIDA.

DESIGN FOR A GAME-BOARD.

49,274.

Specification for Design.

Patented June 27, 1916.

Application filed September 20, 1915. Serial No. 51,724. Term of patent 7 years.

To all whom it may concern:

Be it known that I, FRED N. J. OHLSON, a citizen of the United States, residing at Pierson, in the county of Volusia and State of Florida, have invented a new, original, and ornamental Design for Game-Boards, of which the following is a specification, reference being had to the accompanying drawing, forming part thereof.

The figure is a plan view of a game board illustrating my new design.

I claim:

The ornamental design for a game board, as shown.

FRED N. J. OHLSON.
